SAFETY BELT BUCKLE

Malcolm E. Musser, Jackson Center, Ohio
Application February 21, 1956, Serial No. 40,251
Term of patent 7 years
(Cl. D17—1)

I claim:

The ornamental design for a safety belt buckle, as shown.
